ATOMIZER

Filed Jan. 29, 1930

UNITED STATES PATENT OFFICE

LOUIS V. ARONSON, OF NEWARK, NEW JERSEY, ASSIGNOR TO ART METAL WORKS, INC.,
A CORPORATION OF NEW JERSEY

ATOMIZER

Application filed January 29, 1930. Serial No. 424,246.

My invention relates to atomizers such as are highly practical and efficient in operation.

My invention relates to an atomizer construction having novel characteristics adapting it for medicinal and other uses.

Further objects, advantages and characteristics of my invention will become apparent from the following description taken 10 in connection with the accompanying drawing.

My invention resides in the atomizer, the arrangement of parts and features of construction of the character hereinafter described and claimed.

For an illustration of one of the many forms of my invention, reference is to be had to the accompanying drawing, in which:

Figure 1 is a perspective view of an atomizer constructed in accordance with my invention.

Fig. 2 is a plan view of the atomizer shown in Fig. 1 with the closure cap removed.

Fig. 3 is a vertical sectional view, partly in elevation, and is taken on the line 3—3 of Fig. 2 looking in the direction of the arrows.

Fig. 4 is a vertical sectional view, partly in elevation, and is taken on the line 4—4 of Fig. 2 looking in the direction of the arrows.

Fig. 5 is a horizontal sectional view, partly in plan, and is taken on the line 5—5 of Fig. 4 looking in the direction of the arrows, the liquid receptacle being removed.

Fig. 6 is a fragmentary, perspective view of a latching mechanism for the pump plunger.

Fig. 7 is an enlarged, vertical sectional view of the atomizing conduits.

Referring to the drawing, C represents a casing, housing or container of any suitable configuration and herein shown as comprising a base 1 adapted to rest upon any suitable support or surface, a protective layer 1a of felt or the like being secured to the lower face of base 1 if desired.

Upstanding from the base 1 is the casing 50 lower side wall structure 2 which may be

and preferably is generally circular in horizontal cross-sectional configuration. Preferably, the lower side wall structure 2 terminates at its upper end in a circular flange 2a adapted to support a similar circular flange 3a forming the lower surface of the casing upper side wall structure or cover member 3 which likewise preferably is generally circular in horizontal cross-sectional configuration and shaped to form a throat 55 section which merges uniformly toward the longitudinal axis of said casing C.

The lower and upper side wall structures 2 and 3 are adapted to be detachably secured together in any suitable manner as, for example, by a ring 4 flanged for sliding engagement with the upper surface of flange 3a and threaded so as to be detachably secured to the upper threaded surface of the lower side wall structure 2.

Preferably, the upper side wall structure 3 terminates in a horizontal flat surface 3b, Figs. 3 and 4, having a central perforation through which extends the stem 5a of a member 5 otherwise disposed interiorly of the upper side wall structure 3 and soldered or otherwise suitably secured thereto.

In accordance with a preferred form of my invention, the casing C is divided into lower and upper compartments by a wall or partition 6 extending transversely of the lower side wall structure 2.

Disposed in the lower compartment of casing C is an air pump of any suitable construction. As herein illustrated, the air pump comprises a pump cylinder 7 the longitudinal axis of which is disposed at right angles to the longitudinal axis of the casing C. The pump cylinder 7 is secured in the position illustrated in any suitable manner; in the present case, the lower side wall structure 2 has diametrically aligned perforations receiving opposite ends of said pump cylinder 7 which extends slightly beyond opposite sides of said side wall structure 2 as illustrated particularly in Fig. 3.

One end of the pump cylinder 7 is closed by a section 7a formed preferably integrally therewith, the other end of said pump cylinder 7 being closed by a closure cap 8 pref-

erably threaded thereto and having an exterior actuating section 8a.

The section 7a of the pump cylinder 7 comprises a plunger rod 9 mounted for reciprocal movement thereupon and having an actuating knob 9a at one end thereof. The other end of plunger rod 9, within the pump cylinder 7, may be formed with a threaded terminal of reduced diameter on which is mounted a first disk 10, a second disk 11 of soft leather or the like flanged in the customary manner as shown, and a third disk 12, the disks 10 and 12 being of relatively non-flexible material and serving to clamp the disk 11 therebetween.

Preferably, the pump cylinder section 7a is formed with an air-passing perforation to one side of the plunger rod 9 and the disks 10, 11 and 12 should also be formed with similar perforations, all of the latter being aligned as illustrated. With a construction of the character just described, it is desirable that a member 13 of felt or the like be disposed sidewise against the outer surface of the disk 12 and that a resilient member 14 of sheet metal be disposed sidewise against the layer 13. Thus, as illustrated in Fig. 3, the disks 10, 11 and 12 together with the members 13 and 14 are disposed sidewise in face-to-face relation, a nut 15 threaded to the terminal of plunger rod 9 retaining all of said disks and members in assembled relation as shown.

Any suitable arrangement may be utilized for biasing the pump plunger 9 toward and into the position shown in Fig. 3. As herein illustrated, a helical spring 16 is thus utilized, one end of said spring seating upon the plug 8 and the other end thereof around the nut 15. With the plug 8 detached from the pump cylinder 7, the pump mechanism comprising the disks 10, 11, 12, members 13 and 14, together with spring 16 may be first assembled in said pump cylinder 7 and then the plug 8 threaded into position whereby the various parts are placed in operative relation for manual reciprocation of the plunger rod 9 which, preferably, reciprocates through a member 17 disposed interiorly of the pump cylinder section 7a and suitably secured thereto, the member 17 functioning as a stop.

The pump plunger 9 may be latched or retained in its inner or retracted position in any suitable manner. To this end and as herein illustrated, a headed pin 18 is secured exteriorly to the pump cylinder section 7a for coaction with a lateral lug or member 9b formed on the plunger head 9a. Obviously, the pump plunger 9 may be moved to its inner position whereupon by more or less slight rotation of the head 9a, the member 9b may be latched behind the head of pin 18 as well shown in Fig. 6.

The upper compartment of casing C is

adapted and intended to contain any suitable liquid medium to be atomized by the herein described mechanism. Such liquid medium may be introduced directly into said upper compartment or and preferably, a suitable receptacle or bottle 19 is provided for the purpose described. As herein illustrated, said receptacle 19 is shown as disposed in said upper compartment so that it projects thereabove, said receptacle containing any desired quantity of a suitable liquid medium L. The receptacle 19 may be formed of any suitable material, metallic or otherwise. If formed of metal which reacts chemically with a liquid medium L, it may be suitably coated on its interior surface to prevent such reaction. However, and as illustrated, the receptacle 19, preferably, is formed from glass, or the like.

By preference, the receptacle 19 seats or rests upon a suitable resilient member 20 which may be of a plural-arm configuration such as well illustrated in Fig. 5, the spring member 20, when the parts are in assembled relation, biasing the receptacle 19 upwardly, (see Figs. 3 and 4), so that the outlet through the receptacle neck 19a is closed or sealed by a member or pad 21 of suitable resilient material, as soft rubber, cork or the like. As herein illustrated, the pad 21, to some extent, is detachably secured to the member 5 since the depending stem 5b is received by a centrally disposed perforation formed in said pad 21, said depending stem 5b comprising screw threads, if desired, to enhance the frictional relation thereof with respect to said pad 21.

The upstanding stem 5a of member 5, preferably, is exteriorly threaded so that a member serving in part as a nozzle housing 22 may be threaded thereto, said member 22 comprising an axial passage which may be threaded interiorly at the upper end thereof to receive the threaded shank of a cap member 23. Preferably although not necessarily, said threaded shank of cap member 23 carries a member 24 of cork, soft rubber or the like utilizable as hereinafter described. Furthermore and preferably, the cap member 23 carries a ring 25 loosely swiveled thereon to which is secured one end of a chain 26 or other flexible element, the other end of said chain being connected to an eyelet 27 carried by a suitable part of the casing C.

The aforesaid member 5 is provided with a passage through which a tube or conduit 28 extends, one end of said tube being adapted to depend into the liquid medium L contained by receptacle 19 and the other end of said tube rising above the stem 5a of member 5 and being adapted for enclosure by the nozzle housing 22, the upper end of said tube 28 being closed and being provided im-

mediately therebelow with a laterally extending nozzle 28a.

Adapted for enclosure by the nozzle housing 22 is the upper end of a second tube 29 having a nozzle 29a positioned immediately adjacent the nozzle 28a and angularly related thereto so that it is coactable therewith as hereinafter described. The tube 29 is adapted to communicate with the pump cylinder 7 in the region thereof immediately adjacent the plug 8 and this relation may be obtained in any desired manner such, for example, as herein illustrated wherein the tube 29 extends through the member 5 to a point exteriorly of the upper side wall structure 3 and then depends along the exterior surface thereof to and through the flange 3a and terminates therebelow, somewhat as illustrated in Fig. 3, where it is disposed in telescopic relation with the upper end of a tube or conduit 30 rising from the pump cylinder 7 and communicating therewith immediately adjacent the plug 8. If desired, the stem 5a of member 5 may carry a bushing 31 receiving and closely embracing the upper end of tube 29.

One end of a third tube or conduit 32 is adapted to be disposed within the nozzle housing 22, said tube 32 depending through the member 5 and communicating with the receptacle 19. The tube 32 functions to prevent formation of the partial vacuum within the receptacle 19 during operation of the atomizing mechanism.

The upper side wall structure 3, on its lower interior surface, has a ring or annulus 33 suitably secured thereto, said ring depending slightly below the flange 3a and fitting within the flange 2a as illustrated in Figs. 3 and 4. Carried by the lower surface of flange 3a and surrounding the ring 33 is a packing ring 34 through which the lower end of the aforesaid tube 29 extends.

As illustrated, the nozzle housing 22 forms an enclosure for the upper end of the conduits 28, 29 and 32. In addition, the upper exterior surface of the nozzle housing 22, preferably, is tapered as indicated so that it may be introduced into a nostril, for example, after removal therefrom of the cap 23.

As will be observed, the cap 23, in response to rotary motion, may be removed from the nozzle housing 22, the latter, by similar motion, being removable from the upstanding stem 5a of member 5. The ring 4 may be rotated to release the same from the threads provided on the upper exterior surface of the lower side wall structure 2 whereupon the upper side wall structure 3 may be detached. With the parts thus disassembled, a suitable quantity of a desired liquid medium L, usually but not necessarily a disinfectant, medicinal or soothing agent, may be introduced into the receptacle

19 which may be removed from the lower side wall structure 2 for the purpose if desired. Thereupon, the upper side wall structure 3 may be so placed upon the lower side wall structure 2 that the lower end of tube 29 enters the upper end of tube 30. With these parts thus related, proper rotation of the ring 4 causes the upper and lower side wall structures to be secured together whereby the throat 19a of receptacle 19 is sealed by the pad 21 and the joint between the tubes 29 and 30 is sealed due to the provision of the gasket 34. Thereafter, the nozzle structure 22 and cap 23 may be placed in position in an obvious manner, the cap 23 when suitably threaded into the nozzle member 22 causing the upper end of tube 32 to be sealed by the resilient member 24.

To place the device in operation, the cap 23 is removed and then the knob 9a is rotated slightly to disengage the member 9b from pin 18. After so doing, the casing C may be held in one hand and the pump plunger 8 reciprocated by thumb or finger action thereby pumping air through the conduits 30 and 29, jets of air intermittently passing from the conduit nozzle 29a at relatively high velocity and sweeping past the nozzle 28a of conduit 28 whereby some of the liquid medium L rises through said conduit 28 and is atomized and projected through the upper open end of the nozzle housing 22. Since the receptacle 19, at this time, is open to the atmosphere through conduit 32, it results that the pressure in said receptacle 19 remains at atmospheric value.

After completion of the desired atomizing action, the pump plunger 8 may be latched in its inner position in an obvious manner. This should be done before the cap 23 is placed in position at the end of nozzle housing 22 to minimize or obviate danger of leakage at the upper end of tube 28.

After the cap 23 has been threaded into the position shown in Figs. 3 and 4, the resilient member 24 coacts with the upper open end of tube 32 to prevent accidental or unintended passage of the liquid medium L through said tube 32 such as would be otherwise caused should the atomizer be held in inverted relation.

When the pump plunger moves from right to left, Fig. 3, air is prevented from leaving the pump cylinder 7 by way of the perforations in the disks 10, 11 and 12 due to the fact that such perforations are closed by the members 13 and 14. However, when the pump plunger moves from left to right, Fig. 3, the members 13 and 14, by valve action, permit passage of air interiorly of the pump casing 7 by way of the aforesaid perforations.

As hereinbefore stated, the nozzle housing 22 is detachable from the upstanding stem 5a of member 5. This arrangement is de-

sirable because said nozzle housing 22 may readily be removed to obtain access to the nozzle 28a and 29a so that the passages therethrough may be cleared should either 5 of them become clogged.

While the invention has been described with respect to a certain particular preferred example which gives satisfactory results, it will be understood by those skilled in the 10 art after understanding the invention, that various changes and modifications may be made without departing from the spirit and scope of the invention and it is intended therefore in the appended claims to cover all 15 such changes and modifications.

What is claimed as new and desired to be secured by Letters Patent is:

1. In an atomizer, a casing, a partition dividing said casing into upper and lower 20 compartments, a pump cylinder in said lower compartment, a receptacle in said upper compartment, said receptacle being supported by said partition and removable from said casing, a cover member for said casing, a pad 25 carried by said cover member for closing the top of said receptacle, and means for atomizing liquid contained in said receptacle, said atomizing means comprising an air-passing tube extending from said pump cylinder and a liquid-passing tube extending 30 from said receptacle.

2. In an atomizer, a casing, a partition dividing said casing into upper and lower 35 compartments, a pump cylinder in said lower compartment, the longitudinal axis of said pump cylinder being disposed substantially at right angles to the longitudinal axis of said casing, a receptacle in said upper compartment, said receptacle being supported by 40 said partition and removable from said casing, a cover member for said casing, a pad carried by said cover member for closing the top of said receptacle, and means for atomizing liquid contained in said receptacle, said atomizing means comprising an air-passing tube extending from said pump cylinder and a liquid-passing tube extending 45 from said receptacle.

3. In an atomizer, a casing, a pump cylinder in said casing, the longitudinal axis of said pump cylinder being disposed substantially at right angles to the longitudinal axis of said casing, a receptacle in said casing above said pump cylinder and adapted to 50 contain a liquid medium to be atomized, means for atomizing the liquid medium contained in said receptacle, said atomizing means comprising an air-passing tube extending from said pump cylinder and a liquid-passing tube extending from said receptacle, a cover member detachable from the top of said casing, said cover member 55 controlling the seating of said receptacle in said casing and said receptacle being removable from said casing when said cover mem-

ber is detached from said casing, an external rotatable ring coacting with said cover member and said casing to secure them together, and a nozzle housing carried by said cover member, said tubes extending into and terminating interiorly of said nozzle housing. 70

4. In an atomizer, a casing, a pump cylinder in said casing, the longitudinal axis of said pump cylinder being disposed substantially at right angles to the longitudinal axis of said casing, a transverse wall in said casing above said pump cylinder, a leaf spring disposed on said wall, a receptacle in said casing and seating upon said leaf spring, means for atomizing the liquid medium contained in said receptacle, said atomizing means comprising an air-passing tube extending from said pump cylinder and a liquid-passing tube extending from said receptacle, a cover member detachable from the top of said casing, a pad carried by said cover member for closing the top of said receptacle, and means for attaching said cover member to said casing, said pad, when said cover member is in said last named position, closing the top of said receptacle and biasing said receptacle toward said transverse wall against the action of said leaf spring. 85

5. In an atomizer, a casing, a pump cylinder in said casing, a pump plunger operative in said pump cylinder, said casing comprising a receptacle above said pump cylinder, a cover member removable from said casing whereby a liquid medium may be disposed in said receptacle, atomizing nozzles carried by said cover member, and a conduit leading downwardly from one of said nozzles to said pump cylinder, said conduit comprising sections separable from each other when said cover member is removed from said casing. 95

6. In an atomizer, a casing, a pump cylinder in said casing, a pump plunger operative in said pump cylinder, said casing comprising a receptacle above said pump cylinder, a cover member removable from said casing whereby a liquid medium may be disposed in said receptacle, atomizing nozzles carried by said cover member, a conduit leading downwardly from one of said nozzles to said pump cylinder, said conduit comprising sections separable from each other when said cover member is removed from said casing, adjacent ends of said conduit sections being disposed in telescoping relation when said cover member is on said casing, and means for removably securing said cover member to said casing, said means retaining said conduit sections in telescoped relation. 110

In testimony whereof I have signed my name to this specification.

LOUIS V. ARONSON.
